D. R. MCKILLCAN

SHROUDED AGITATOR

Filed April 7, 1921

Patented Dec. 11, 1923.

1,477,201

UNITED STATES PATENT OFFICE.

DONALD R. MCKILLICAN, OF NEW YORK, N. Y., ASSIGNOR TO MECHANICAL MIXERS CORPORATION, OF NEW YORK, N. Y., A CORPORATION OF DELAWARE.

SHROUDED AGITATOR.

Application filed April 7, 1921. Serial No. 459,238.

To all whom it may concern:

Be it known that I, DONALD R. MCKILLICAN, a citizen of the United States, residing in the city of New York, county of New York, and State of New York, have invented a new and useful Improvement in Shrouded Agitators, of which the following is a specification.

My invention relates broadly to agitators for the intimate mixing of substances in general, more particularly to the mixing of food products, and specifically to soda fountain drink mixers.

Reference is made to my co-pending application for agitators, filed January 27th, 1921, Serial No. 440,293, upon some of the parts of which my present invention is an improvement.

The object of my invention is to provide an improved agitator having several cooperating features of superior efficiency designed for general utility and particularly adapted for incorporation in improved soda fountain drink mixers, the details of which will appear more fully from the following description of the preferred construction and be pointed out in the claims.

Referring to the accompanying drawings:

Fig. 1 is a perspective view of the agitator with the shaft omitted;

Fig. 2 is a cross-sectional plan of the agitator mounted in a soda fountain shaker, taken on the line 2—2 of Fig. 3, looking in the direction of the arrows;

Fig. 3 is a view of same in cross-section, taken on the line 3—3 of Fig. 2;

Fig. 4 is an end view of the agitator mounted on the shaft; and

Fig. 5 is a cross-sectional view of the universal joint of the agitator coupling, taken on the line 5—5 of Fig. 2.

The agitator consists of a pair of paddles indicated by the numerals 1—1, which are notched together and held in slots at the end of a shaft 2. The paddles 1—1 are provided with breaker points 3, outside of which are provided flow guide rings 4—4, outside of which and at the end of the paddles is provided a shroud ring 5. The above-mentioned parts are preferably made of brass and soldered together to form the complete agitator by being dipped in molten tin.

The shaft 2 extends to the right from the paddles 1—1 and is formed into a col-

lar 6, which abuts against the left end of a bearing 7. The bearing 7 is enlarged and soldered at the enlarged portion 8 to the side of the shaker cup 9. The shaft 2 extends to the right beyond the collar 6 and terminates in a ball pointed end portion 10, the shaft 2 being pinned by a pin 11 into a sleeve 12, which is formed into a cone 13 at its left end. The cone 13 mates with a corresponding cone seat 14 in bearing 7, thus tending to prevent leakage along the shaft 2 from shaker cup 9.

Sleeve 12 is provided with a flange 15 to throw off any leakage which may occur from cup 9, flange 15 being contained within a recess 16 at the right-hand portion of bearing 7, so that any leakage which may be thrown off is confined in the recess 16. At the bottom of recess 16 is provided a drip slot 17, which conducts such leakage as may occur, to the catch basin 18, which is soldered to the shaker cup 9, as best shown in Fig. 3. The right end of sleeve 12 is formed into a spherical portion 19, which is contained within a hollow cylindrical portion 20 of the male portion 21 of a cone clutch. At the right of the hollow cylindrical portion 20 an internal flange 22 is formed, which bears at its left inner edge against the spherical portion 19 of sleeve 12 and a screw 23 is threaded into sleeve 12 and abuts against the shaft end 10, while the head is close enough to the inner right edge of internal flange 22 to permit only a limited motion of the hollow cylindrical portion 19 of sleeve 12. Thus the male cone clutch member 21 has a limited universal motion with respect to sleeve 12.

The spherical portion 19 of sleeve 12 is partly cut away in the form of a partial cylinder 24, having its axis perpendicular to that of shaft 2, best shown in Figs. 3 and 5, to form abutting surfaces for the ball points of screws 25—25, which are threaded into the clutch member 21, and prevent its rotation with respect to sleeve 12 and shaft 2, but do not otherwise restrict the motion between clutch member 21 and sleeve 12.

Referring particularly to Figs. 2 and 3, arrows indicate the flow of the substances to be agitated.

The paddles 1—1 and the rings 4—4 cause a flow of the substances like that in the impeller of a centrifugal pump and the shroud ring 5 deflects them, as indicated by the

arrows, thus preventing splashing out of the top of the cup 9, while the breaker points 3 materially assist in breaking up lumps such for instance as lumps of ice cream.

5 The mounting of the shroud ring 5 on the paddles 1-1 has been found to increase the efficiency of the device as compared with agitators having stationary housings and to make the assembly of the several factors 10 in the shaker cup 9 more convenient and practical.

Modifications of this invention and the incorporation of its novel features, as expressed in the claims, with other devices 15 may be made without departing from the spirit of the invention.

I claim:

1. An agitator provided with a shaft, and

having intake openings in both sides of the 20 agitator at the shaft for entrance of the materials to be agitated, a flow guide member surrounding each of the intake openings and a shroud member mounted at the periphery of the agitator to rotate therewith and to deflect the direction of flow of the 25 materials.

2. An agitator provided with a shaft, and having an entrance opening at the shaft for the materials to be agitated, a flow guide member at the side of the agitator, a breaker point near the flow guide member and a shroud member mounted at the periphery of the agitator to rotate therewith and to deflect the direction of flow of the materials 30 to be agitated.

DONALD R. MCKILLICAN.
